[57]

ABSTRACT

A fluid energy mill comprising a lower inlet section and an upper classification section connected by a vertical upstack on one side and a vertical downstack on the other side, the inlet section having tangential nozzles connected to a source of gaseous fluid pressure and a raw feed inlet, whereby the raw feed particles are entrained and centrifugally whirled around the mill by the pressure fluid. The portion of the inlet chamber adjacent the upstack, as well as the upstack itself and the portion of the classification chamber adjacent the upstack form part of an antifriction curve. The classification section is preferably generally circular and has at least one exhaust outlet in the center so that the lighter particles on the inner periphery of the centrifugal path are rotated in a helical path until exhausted through the outlet. Preferably, nozzles are provided in the classification section to project pressure fluid thereinto in a generally elliptical path.

CONSTANT ACCELERATION FLUID ENERGY MILL

This invention relates to a fluid energy mill, and it particularly relates to an improved fluid energy mill wherein the acceleration of the particles in the centrifugal path is better controlled and wherein the exhausting of the lighter particles from the mill is made more effective and efficient.

Fluid energy mills, as such, are now well-known and are in extensive use. Many of these mills comprise a vertically elongated generally arcuate construction including straight, elongated upstack and downstack sections connected at top and bottom by arcuate elbow sections. Nozzles lead into the lower elbow portion from a source of gaseous fluid under pressure. These nozzles are tangentially directed relative to the path of flow through the lower elbow, or inlet, section, and all or some of them may be so positioned that the fluid jets issuing therefrom intersect each other, whereby a greater grinding or pulverizing effect is obtained. The inlet section is also provided with a feed inlet for the solid pulverulent material being ground or otherwise treated; this feed inlet being so arranged that the feed path intersects the fluid jet streams, so that the particles are entrained thereby and are not only ground or otherwise treated by action of the fluid, but are also circulated through the mill by the tangentially directed fluid stream.

During the aforesaid type of action, the centrifugal force of the circulating fluid and particles carries these particles into a classification zone where they are centrifugally separated into smaller and larger particles, the smaller, lighter particles tending to remain on the inner periphery of the circulating stream while the larger, heavier particles tend to remain on the outer periphery. This centrifugal separation is utilized to remove the lighter particles from the mill while recirculating the heavier particles for an additional pass through the mill to effect further pulverization or other treatment thereof. This is achieved by providing an exhaust duct on the inner periphery of the mill adjacent the entrance to the return stack. As the centrifugal action carries the particles past this exhaust duct, the lighter particles on the inner peripheral portion of the stream flow through the exhaust duct and are removed from the mill, while the heavier particles on the outer peripheral portion of the stream pass back into the inlet section and, after being intermixed with additional raw material, are again subjected to the pulverizing action of the fluid jet streams.

A problem in the above type of mill has always been the fact that the exhausting of the lighter particles has been somewhat inefficient because a significant portion of these lighter particles was carried down with the heavier particles for further treatment. This not only wasted energy on particles which were already sufficiently treated, but tended to over-pack the treating zone so that the heavier particles, which were being recycled, and the additional raw feed were not sufficiently treated.

Another disadvantage of prior fluid energy mills was inherent in their construction whereby the particles moved from an arcuate treating zone through a substantially straight vertical upstack into an arcuate classification zone. The sudden difference of curvature between the treating zone and the upstack not only caused many of the particles to continue, on their momentum, to strike the walls of the upstack, thereby causing undue wear, but also resulted in a sudden loss of acceleration of the particles, whereby many fell, under the influence of gravity, back into the treating zone. The same wear effect resulted from the sudden change of curvature between the vertical upstack and the classification zone.

In addition, the loss of centrifugal energy and acceleration as the particles moved through the substantially straight, vertical upstack interfered with the efficient separation of the lighter and heavier particles in the classification zone.

It is, therefore, one object of the present invention to provide a fluid energy mill which has an improved means for separation of lighter from heavier particles and a more effective means for exhaustion of the lighter particles from the mill.

Another object of the present invention is to provide a fluid energy mill which reduces wear on the interior surfaces of the

mill and which more effectively maintains a substantially constant deceleration and acceleration of the particles as they pass through the mill.

Other objects and many of the attendant advantages of this invention will be readily appreciated as the same becomes better understood by reference to the following description when read in conjunction with the accompanying drawings wherein:

FIG. 1 is a sectional view of a mill embodying the present invention.

FIG. 2 is a sectional view taken on line 2-2 of FIG. 1.

FIG. 3 is a sectional view taken on line 3-3 of FIG. 1.

FIG. 4 is a sectional view taken on line 4-4 of FIG. 1.

FIG. 5 is a fragmentary sectional view of a modified form of the mill of FIG. 1.

FIG. 6 is a sectional view taken on line 6-6 of FIG. 5.

FIG. 7 is a fragmentary sectional view of an alternative embodiment of the present invention.

FIG. 8 is an illustration of the anti-friction curve used in the construction of the mill.

Referring now in greater detail to the various figures of the drawings wherein similar reference characters refer to similar parts, there is shown in FIG. 1 a mill, generally designated 10, comprising a lower inlet section 12, an upstack 14, a classification section 16 and a downstack 18.

The inlet section 12 is arcuate in length conforming to the initial portion of the "Tractrix" or "Schiele's anti-friction curve." This curve is described, for example, in "The Mechanical Engineering Handbook"; Kent; 9th Ed.; 1948; John Wiley & Sons, Inc.; page 50. This section is also generally V-shaped in cross section (as best seen in FIG. 4), with the radially inner wall 20 being wider than the outer wall 22, the inner and outer walls being connected by inclined side walls 24 (as best shown in FIG. 4). A series of nozzles 26 are provided for the inlet section 12, these nozzles being preferably at varying inclined angles to the inlet section and being in fluid connection with a manifold 28 that is connected to a source of gaseous fluid under pressure (not shown) by means of a conduit 30.

The upstack 14, which is integral with the inlet section 12, is provided with a gradual curvature that is a continuation of the anti-friction curve of the inlet section 12. The curvature of the upstack 14 is such that particles being centrifugally whirled through the inlet section 12 will continue on their centrifugal path without any significant number of them striking either the inner or outer walls of the upstack.

In addition to having the aforesaid anti-friction curvature, the upstack 14 has a generally V-shaped cross section wherein the inner wall 32 (as best shown in FIG. 3) is wider than the outer wall 34 and is connected thereto by inclined side walls 36. This configuration is a continuation of that of the inlet section 12.

The upstack 14 merges into the classification section 16 by means of the outer wall 38 of the classification section 16.

The classification section 16, in addition to being bounded by the arcuate outer wall 38, is also bounded by a reversibly arcuate inner wall 40, the two arcuate walls forming a generally elliptical classification chamber.

At the center of the classification section 16 there is provided an exhaust opening 42 on each side. Each exhaust opening 42 mates with an exhaust duct 44 (as best seen in FIG. 2). Both ducts 44 may be connected to a common exhaust manifold (not shown). In the lower wall 40 are provided one or more (here shown as two) angular nozzles 46 which are so inclined as to project jets of gaseous fluid to follow the elliptical path formed by the classification section 16 around the exhaust openings 42. These nozzles are connected to any desired source of gaseous fluid under pressure. They are here illustrated as being connected to the manifold 28 by ducts 47. The nozzles 46, although preferably provided, are optional, and may be omitted, although such omission would prevent the most effective circulation within the classification section.

The downstack section 18 has a cross-sectional shape similar to that of the upstack section, whereby the outer wall 48 (as best seen in FIG. 3) is wider than the inner wall 50 and is connected thereto by inclined side walls 52. However, it is not as wide as the upstack because less space is required for centrifugal acceleration and because only the heavier pass therethrough.

The downstack 18, instead of having an anti-friction curvature, is vertically substantially straight. This is because separation has already taken place in the classification section and, since all the particles passing through the downstack are heavy and are being returned to the inlet section, the straight vertical drop takes advantage of the action of gravity in increasing the acceleration of the downwardly moving particles.

A feed inlet 54 leads into the inlet section 12 at the juncture of the inlet section with the downstack 18. This feed inlet is shown as comprising a hopper 56 connected to a Venturi tube 58 and provided with a nozzle 60 connected through a valve 62 to a source of gaseous fluid under pressure; whereby the gaseous fluid propels the particles from the hopper 56 through the Venturi tube 58, where they are accelerated, into the mill. However, any other desirable type of feed means may be substituted within the scope of the invention.

In operation, the raw pulverulent material is fed into the mill through the inlet 54 and is entrained by the gaseous fluid jets from nozzles 26. Since the nozzles 26 are at variable angles relative to each other, the jets intersect and increase the tendency of the particles to impact against each other and pulverize each other. At the same time, since the nozzles are so inclined that the general direction is to the left (as viewed in FIG. 1), the particles are centrifugally whirled into the upstack 14.

The anti-friction curvature prevents abrasion of the mill walls by the particles and also acts in the upstack to decelerate the upward movement of the particles, so that movement of the largest particles in the upstack are retarded and these particles, therefore, drop back into the inlet chamber for further treatment.

As the particles and entraining gaseous fluid move into the classification section 16, the curvature of the mill increases, thereby increasing the acceleration of the particles and fluid. This acceleration is usually sufficient to cause the lighter particles to rotate around the central openings 42 in a helical path until they pass through the openings closest thereto. This action is aided by the fact that since the fluid exhausts through the center opening 42, the viscous drag of the spiraling fluid overcomes the centrifugal force on the lighter particles and helps to carry them out through the opening 42. At the same time, the increased centrifugal force carries the heavier particles around the outer periphery of the centrifugal path and down into the downstack 18 where they are mixed with fresh material from the inlet 54 and pass into the inlet section 12 for further grinding.

The nozzles 46 are preferably used to further increase the centrifugal acceleration of the particles and fluid in the classification section, whereby the heavier particles are more thoroughly urged toward the outer periphery while the lighter particles are given a greater rotational acceleration to increase their helical movement toward the central exhaust openings, thereby further classifying the mass of particles to give a still finer end product.

In FIGS. 5 and 6 there is shown a modified form of the mill described above, wherein the mill, generally designated 100, is the same as that of FIG. 1 except that in the classification section 102 there is a transverse rotatable open-ended tube 104 which extends laterally through the section 102. The tube 104 is provided with a slot 106 on its underside. The slot 106 is in communication with the chamber formed by the classification section 102 and permits entrance into the tube 104 of the helically travelling lighter particles. The rotatability of the tube 104 permits the slot 106 to be adjusted into any desirable position.

The construction of FIGS. 5 and 6 permits the helically travelling particles to pass directly into the exhaust opening which is in their helical path, instead of having to make a lateral turn in order to pass into the lateral openings 42 provided in the form of the mill shown in FIGS. 1-4, thereby refining the end product.

In FIG. 7 there is shown an alternative form of the mill of FIG. 1 wherein the mill, generally designated 200, has the same anti-friction curvature, such curvature being partially indicated at 202. However, instead of the elliptical classification section with a central opening, there is provided a classification section 204 which is an arcuate section similar to the inlet section but having a generally V-shaped cross section reverse to that of the inlet section (not shown), this inlet section having the same construction as the inlet section 12 in the mill of FIGS. 1-4. The exhaust opening is provided at 206 in the standard manner.

The gaseous fluid used is a matter of choice depending upon the material being treated and the results desired. The fluid may, for example, be air, steam, an inert gas or vapor, or any other desirable and feasible gas or vapor, the term "gaseous fluid" being generic to all gases and vapors. The gaseous jets may be ejected from the nozzles either under high velocities of the acoustic or super acoustic range, or lower velocities, depending on whether a greater or lesser degree of grinding is desired, and also depending on the construction of the nozzles. The particular construction of the nozzles themselves is standard and may be of the so-called "convergent-divergent" type or the "abrupt" type depending on the velocities desired; the "convergent-divergent" type being of a generally Venturi shape and providing higher velocities.

Although this apparatus has been described primarily for grinding or pulverizing, it may also be used for such other purposes as drying, chemical reactions, coating, agglomerating or deagglomerating, and many other functions, depending on the type of gaseous fluids used, the materials fed into the mill, the velocities and pressures of the gaseous fluids as they pass into the mill, the angles of incidence of the nozzles relative to the interior of the mill, etc. For example, if a very hot, low pressure gaseous fluid were used, there would be little or no grinding but only a drying of the particles, if wet. Such drying, itself, causes the formation of lighter and heavier particles because it removes adherent liquid which acts as an adhesive between particles of varying sizes. In addition, the gaseous fluid may be of a type to chemically react with the treated material. Or particles of different chemical composition may be simultaneously used whereby, upon impact, they may physically adhere or chemically combine.

It is to be further noted that although the mill is illustrated as being vertical, this being the preferred position, it may also be utilized in the horizontal or any other desired position.

The material being treated may be either pulverulent solid material, a liquid slurry or even a liquid wherein the liquid may be broken up into liquid particles by the atomizing effect of high velocity gases, or it may be a combination of such materials.

The invention claimed is:

1. A fluid energy mill comprising an inlet section, a classification section, an upstack section connecting one end of said inlet section to one end of the classification section, and a downstack section connecting the other end of said inlet section to the other end of the classification section, tangentially arranged nozzles leading into said inlet section from a source of gaseous fluid under pressure, a feed inlet leading into said inlet section for inserting raw material into said mill, at least one exhaust outlet in said classification section, said exhaust outlet being adjacent the inner periphery of the centrifugal path of particles and fluid being propelled through said mill, and said inlet section and upstack section having a continuous tractrix antifriction longitudinal curvature.

2. The mill of claim 1 wherein said classification section is generally circular and said exhaust outlet is positioned in the center thereof.

3. The mill of claim 2 wherein there are two exhaust outlets, one at each side of said classification section.

4. The mill of claim 2 wherein said exhaust outlet comprises an open-ended tube extending transversely through said classification section, said tube having a slot therein which is in communication with the interior of said classification section.

5. The mill of claim 1 wherein said classification section is longitudinally arcuate and wherein the exhaust outlet is adjacent the said other end of the classification section.

6. The mill of claim 1 wherein inclined nozzles, connected to a source of gaseous fluid under pressure, lead into said classification section.

7. A method of treating pulverulent material in a mill which comprises propelling the particles of said material through an inlet zone, wherein they are entrained in and acted on by gaseous fluid injected into said inlet zone in directions that are tangential to the initial path of said particles, passing the resultant

particles from said inlet zone through a curved path which is defined by a tractrix antifriction curvature, and then passing the particles through a classification zone which is defined at least partially by a continuation of said tractrix curvature, said particles being separated into heavier and lighter particles within said classification zone, and said lighter particles being passed through an exhaust outlet from said classification zone.

8. The method of claim 7 wherein the classification zone forms an elliptical path in which the heavier particles are centrifugally held on the outer periphery of said path while the lighter particles are centrifugally held on the inner periphery of said path, said lighter particles being exhausted from said inner periphery.

9. The method of claim 7 wherein additional gaseous fluid is injected into said classification zone in a direction to accelerate the movement of the lighter particles.
